UNITED STATES PATENT OFFICE

TALMA T. GREENWOOD, OF EAST TEMPLETON, MASSACHUSETTS, ASSIGNOR TO CONDIT ELECTRICAL MANUFACTURING CORPORATION, OF SOUTH BOSTON, MASSACHUSETTS, A CORPORATION OF MASSACHUSETTS

THERMAL RELAY

Application filed November 30, 1928. Serial No. 322,703.

This invention relates to thermal relays of the type having a heating element and a thermally expandable member which is adapted to be heated by said element and expand to move either into or out of cooperative relation with a contact member to control the circuit which includes said contact member.

Heretofore the operative parts of such relays have been built into an enclosing casing, usually of tubular shape, the casing constituting a support in which various components of the relays were independently mounted and secured in cooperative relation with each other. It is sometimes necessary to inspect relays of this type either to change the setting of the relays, to clean the contacts, or for various other purposes. This cannot be done conveniently when the various parts of the relay are independently mounted on the enclosing casing. In particular, the various parts can not be removed from the casing and operated under working conditions and their manner of operation ascertained since some of the essential parts, and particularly the stationary contact member, are carried by the casing and the relay is consequently disabled when the casing is removed.

It is an object of the present invention to provide a thermal relay of the general type above set forth wherein the operative parts of the relay are mounted in a unitary manner on a supporting structure so that the structure can be inserted into and withdrawn from the enclosing casing as a unit and without the necessity for disassembling the working parts of the relay.

A further object of the invention is the provision of a thermal relay having an enclosing casing provided with a plurality of terminals and the operating mechanism of the relay mounted as a unitary structure and so arranged that when it is within the casing it is removably connected with the proper casing terminals.

Another object is generally to improve the construction and operation of thermal relays.

Fig. 1 is a side elevation of a thermal relay embodying the invention.

Fig. 2 is an end elevation of a thermal relay

supported removably in fuse clips of the cartridge type.

Fig. 3 is a longitudinal sectional elevation of the relay of Fig. 1.

Fig. 4 is a section along lines 4—4 of Fig. 3. 55

Fig. 5 is a perspective view of the removable unit of Fig. 3.

Fig. 6 is a plan detail of the intermediate internal contact of Fig. 3.

As herein shown the thermal relay embodying the present invention includes a tubular insulating casing 10 having screw-threaded ends on which are removably screw threaded end caps 12 and 14 which constitute the two line terminals of the relay. 60 65

A ring 16 encircles said insulating casing near one end thereof and is spaced and insulated from both terminal caps and constitutes the third or pilot-circuit terminal of the relay. The end caps 12 and 14 and the intermediate terminal 16 are adapted to be received in fuse clips 18 of a suitable supporting member 20 for connection with their respective circuits. 70

The operative parts of the relay are adapted to be received removably, as a unitary structure, within the enclosing casing 10 and in electrical connection with the terminals thereof. The unitary relay structure is shown removed from the enclosing casing 80 in Fig. 5 and is shown within the casing in cooperative relation with the terminals thereof in Fig. 3. Said unitary relay structure includes an insulating bar 22 which constitutes a support for the various parts of the device. A disc 24 is located at one end of said insulating bar. Said disc has a diameter greater than the internal diameter of the enclosing casing 10 and is adapted to lie against one end of said casing within the end cap 12 90 and to be clamped releasably against the end of said casing by said end cap as shown in Fig. 3. Said disc has an ear 26 struck out therefrom and an elongated opening 28 vacated by the material of said ear. Said ear is reflexed at right angles with the body of the disc and is secured to said insulating bar by a suitable means as the clamping bolt 30. A second disc 32 is located at the other end of said bar 22 and has a similar ear 95 100

Fig. 2 is an end elevation of a thermal relay

struck out at right angles from the body of the disc and an opening 36 vacated by the material of said ear. Said ear 34 is secured to the end of the bar 22 by suitable means as the attaching bolt 38. Said latter disc has a diameter approximately equal to the internal diameter of the insulating tube so that it can pass freely therethrough from one end to the other. When the relay structure is located in operative position within the casing the disc 32 is adapted to project slightly beyond the end of the insulating casing so that when the end cap 14 is screwed on the casing it will make firm engagement and electrical contact with said disc.

An electrical heating element herein shown as consisting of a reflexed flat strip 40 of resistance material overlies the top face of said insulating bar and has its ends connected electrically with the end discs 24 and 32 by means including the aforesaid bolts 30 and 38. A thermally expandable member 42, consisting of a strip composed of two metals having dissimilar coefficients of expansion secured together back to back, overlies said heater element 40 and is in heat receiving relation therewith. One end of said thermally expandable member is fixedly secured in the aforesaid relation by the aforesaid clamping screw 30 and thus is in electrical connection with the heater element and the disc 24. The free end of said thermally expandable element is provided with a contact member 44. A generally cylindrical or ring-shaped contact support 45 surrounds the insulating bar 22 and the contact carrying end of the thermally expandable element and is fixed to said insulating bar by a suitable means as the screw 46. A portion of said ring is located above the free end of said expandable element and has a downwardly-directed apertured boss 48 in which a contact 50 is adjustably screw threaded. Said contact member 50 is in cooperative relation with the movable contact member 44 of the thermally expandable element whereby, when said element is suitably heated by said heater member 40, it will expand and either make or break its engagement with the fixed contact member 50 depending upon the direction in which said thermally expandable member is arranged to flex when suitably heated. A ring 52 is located within and is carried by the casing underlying the intermediate terminal 16 and is connected electrically with said terminal and is fixed within the casing by suitable means as a rivet 54. Said ring may be provided with one or more downwardly directed spring fingers 56 that are adapted to engage the contact support 45 and thus connect said support and the contact member carried thereby electrically with the intermediate terminal 16. As thus arranged the unitary relay structure as illustrated in Fig. 5 can be inserted as a unit within the casing and

the stationary contact 50 will be automatically located in electrical connection with the intermediate terminal 16 of the casing. When the end caps 12 and 14 are in place the end discs 24 and 32 of the unitary structure are in electrical contact with the end caps so that, when the relay is inserted in the holding clips of the member 20, it automatically establishes connection with the circuits of the relay. The operative parts of the relay structure thus are seen to be supported entirely independently of the enclosing casing so that the structure can be withdrawn from the casing and inspected, the contacts adjusted and cleaned, and the operation of the relay observed entirely independently of the casing.

I claim:

1. A thermal relay including the combination of an enclosing casing having terminals removably secured thereto, and a unitary relay structure movable into and out of said casing including cooperating contact members and a thermo-responsive member for controlling said contact members, and having end terminal members adapted to be held detachably between and in pressure engagement with said casing terminals.

2. A thermal relay including the combination of an enclosing casing having terminals at least one of which has a screw-threaded connection with said casing, and a unitary structure including a support having terminals, separable contact members carried by said support, and a thermally-expansible element for operating said contact members, said unitary structure being movable into and out of said casing and its terminals being held in detachable engagement with said casing terminals by said screw-threaded casing terminal.

3. A thermal relay including the combination of a tubular enclosing casing having end terminals which have removable screw-threaded connections with said casing, and a unitary relay structure movable into and out of said casing having end terminals which have detachable connections with said casing terminals and which are held in engagement with said casing terminals by the screw-threaded connections thereof with said casing.

4. A thermal relay having the combination of a tubular enclosing casing having terminals connected therewith, and a unitary relay structure independent of said casing and its terminals movable into and out of said casing as a unit having separable contact members and terminals which have detachable connections with said casing terminals, said casing terminals having means which releasably retains said unit within said casing with the terminals thereof in axial pressure engagement with said casing terminals.

5. A thermal relay having the combination

of an enclosing casing having three spaced terminals connected therewith, and a unitary relay structure movable as a unit into and out of said casing and into and out of engagement with said terminals, said unitary structure including a support, three spaced terminals carried thereby, a heater element connected with two of said terminals, a thermally expandible element carried by said support and connected with one of said terminals, and a stationary contact member cooperating with said expandible element connected with one of said terminals, said terminals having detachable engagements with the terminals of said casing and being retained in said casing in axial pressure engagement with said casing terminals by one of said casing terminals.

6. A thermal relay having the combination of an enclosing casing having end terminals and an intermediate terminal connected therewith, and a unitary relay structure removably located within said casing having a support, terminals carried by said support detachably engaged with said end terminals of said casing, an intermediate terminal carried by said support having a detachable engagement with said intermediate casing terminal, a heater element connected electrically with said support end terminals, a thermally expandible element connected with one of said support end terminals, and a fixed contact member carried by said intermediate support terminal and cooperating with said expandible element.

7. A thermal relay including the combination of an enclosing casing having an intermediate external terminal, a unitary relay structure located removably within said casing including a thermally expandible member, a fixed contact member controlled thereby, end caps removably located on the ends of said casing at least one of which has an electrical connection with said expandible member, and means establishing a breakable connection between said fixed contact member and said intermediate terminal in any relative angular relation between said relay structure and casing.

8. A thermal relay having the combination of a tubular enclosing casing, end caps removably screw-threaded thereon constituting end terminals of the relay, an intermediate terminal carried by the casing between said end caps, and a removable unitary relay structure located within said casing including a support having end terminals in removable engagement with said end caps, said support having an intermediate terminal which is detachably connected with said intermediate casing terminal, a fixed contact member carried by said intermediate support terminal, a thermally-expandible member cooperating with said contact member and connected with one of said support end ter-

minals, and a heater element connected with both of said support end terminals, said end caps constituting means to secure said relay structure removably within said casing.

9. A thermal relay having an enclosing casing including terminal members, a removable unitary relay structure therefor including separable contacts, a thermally-expansile element controlling said contacts, and means including said terminal members, at least one of which has a screw-threaded connection with said casing, for removably securing said unitary structure within said casing.

10. A thermal relay having an enclosing casing, a removable unitary relay structure therefor including separable contacts, a thermally-expansile element controlling said contacts, and means screw-threaded to said casing for removably securing said unitary structure within said casing, which means also constitutes a terminal of said relay.

11. A thermal relay having an enclosing casing, a removable relay unit having a thermo-responsive member, separable contacts controlled by said member, rigidly spaced terminals at the opposite ends of said unit, end caps which are detachably located on the ends of said casing and bear against said terminals, and means which connects said end caps to said casing and which forces them axially of the casing against said terminals.

12. A thermal relay including the combination of an enclosing casing, a removable relay unit having terminal members at the ends which engage and center the unit in the casing, a thermally responsive element and cooperative contact members controlled thereby forming a part of said unit, and removable end caps on the ends of the casing which hold the unit therein, at least one of said end caps having a screw-threaded connection with said casing whereby to effect axial pressure engagement between said terminal members and end caps.

13. A thermal relay comprising an enclosing casing, a removable relay unit having end terminal members, an insulating bar which rigidly connects and spaces said members, a thermo-responsive member and contacts controlled thereby forming a part of said unit, and end caps which are removably screw-threaded on the ends of said casing and which exert a clamping pressure on said terminal members to retain said unit removably in said casing and to establish electrical connection between said terminal members and end caps.

14. A thermal relay including the combination of a tubular enclosing casing open at the ends, a unitary relay that is adapted to be inserted and removed through an open end of said casing having end terminal members which are located at the ends of said casing, a thermo-responsive member and con-

tacts controlled thereby connected mechanically with said end terminal members, a line terminal forming a closure for one end of said casing and constituting an abutment for the terminal member at one end of said relay, and a second line terminal having screw-threaded connection with the opposite end of said casing arranged to close said casing and clamp relay terminals between and into pressure engagement with said casing line terminals.

15. A thermal relay including the combination of a tubular enclosing casing having end terminals, at least one of which has an axial screw-threaded connection with said casing, a unitary relay structure removably received in said casing, including a support having terminals at its ends constituting abutment contact members which are adapted to cooperate with the end terminals of the casing, a thermo-responsive member and separable contacts controlled thereby connected with said support, said screw-threaded terminal constituting clamping means for holding said relay detachably in terminal engaging position in said casing.

16. A thermal relay including the combination of a tubular enclosing casing open at one end, a unitary relay structure removably received in said casing through the open end thereof including end terminals, a thermo-responsive device and separable contacts controlled thereby connected mechanically with said end terminals, and terminal members carried by the ends of said tubular casing having a detachable connection with said relay terminals, at least one of said casing terminals having a connection with said casing by which it is progressively movable axially of said casing to effect clamping engagement between said relay and casing terminals.

17. A thermal relay including the combination of a tubular enclosing casing open at one end, a unitary relay structure removably received in said casing through the open end thereof including end terminals and an intermediate terminal, a thermo-responsive element and separable contact members controlled thereby forming a part of said structure, terminal members carried by said casing having a breakable connection with the corresponding terminals of said relay, one of said terminal members having a screw-threaded connection with said casing and constituting means to urge said relay structure axially of said casing and similar terminals of said casing and relay into good electrical engagement.

18. A thermal relay including the combination of a tubular casing having a terminal intermediate its ends, a unitary relay structure arranged to be inserted into and removed from said casing as a unit including end terminals and an intermediate terminal having a breakable connection with said in-

termide casing terminal, a thermo-responsive member and separable contacts controlled thereby connected mechanically with said end and intermediate terminals, end terminals carried by said casing arranged to make engagement with the end terminals of said relay, at least one of the end casing terminals having a screw-threaded connection with the casing and constituting clamping means for effecting pressure engagement between the end terminals of relay and casing.

19. A thermal relay including the combination of an enclosing casing, an end cap on one end of said casing, a relay unit which is insertible in said casing having end terminals one of which bears against said end cap, means rigidly connecting and spacing said terminals, a thermo-responsive device and separable contacts controlled thereby connected mechanically with said terminals, and a second end cap which is screw-threaded onto the other end of said casing and which bears onto said other end terminal and clamps said unit between it and said first end cap.

20. A thermal relay including the combination of an enclosing casing, a relay unit having end terminals one of which is small enough to be removed through said casing and the other of which is too large to enter said casing, means rigidly connecting and spacing said end terminals, a thermo-responsive member and separable contacts carried by said means, an end cap which is screw-threaded on one end of said casing and which clamps said large terminals between it and the end of said casing, and a second end cap which overlies and bears against said small terminal.

In testimony whereof, I have signed my name to this specification.
